UNITED STATES PATENT OFFICE.

JOSEPH KIRKLEY AND FRANK A. WHITE, OF AUGUSTA, GEORGIA.

UMBRELLA STRUCTURE.

1,029,449.

Specification of Letters Patent. Patented June 11, 1912.

Application filed June 21, 1911. Serial No. 634,422.

To all whom it may concern:

Be it known that we, JOSEPH KIRKLEY and FRANK A. WHITE, citizens of the United States, residing at Augusta, in the county 5 of Richmond, and State of Georgia, have invented new and useful Improvements in Umbrella Structures, of which the following is a specification.

This invention relates to umbrella structures, and has for an object to provide an umbrella which will include a novel form 10 of notch and runner respectively, each embodying companion elements which are adapted to coöperate with each other to 15 form an effective housing for the rib and stretcher ends and which will operate to securely confine and retain the ends without resorting to the use of permanent fastening devices to be engaged with the ribs and 20 stretchers respectively.

In the drawing, forming a portion of this specification and in which like numerals of reference indicate similar parts in the several views: Figure 1 is a side view of a portion 25 of an umbrella stick showing the runner and the notch applied thereto. Fig. 2 is a horizontal section on line 2—2 of Fig. 1. Fig. 3 is a section through the rib. Fig. 4 is a similar view showing a slightly modified form of rib.

The umbrella stick 1 may be of any suitable well known construction. The notch 2 comprises companion elements 3 and 4, the former having formed integral therewith a 35 substantially cup portion 5 which is arranged beneath the concavity in the cup 6 in the element 4, the said cup portions having fitted therein the spherical upper ends 7 of the ribs 8. Upon reference to Fig. 3 of the 40 drawing, it will be seen that the ends 7 are constructed as an integral part of the rib.

In the form of the rib shown in Fig. 4, the spherical end 9 is hollow, the walls 10 thereof being clamped or otherwise suitably 45 secured to the portion 11 of the rib.

The element 3 of the notch has formed thereon a circular shoulder 12 against which the element 4 is engaged so as to hold the cup 6 suitably spaced from the cup 5 to 50 permit of the effective movement of the rib. The elements 3 and 4 of the notch are se-

cured to each other to the stick 1 by the rivet 13 or any other suitable well known fastening device. The spherical heads 7 of the ribs are provided with integral projecting 55 portions 14 formed at an angle to the ribs and which are movable in the slots 15 in the cup 6 and in the slots 16 in the cup 5. These ribs are substantially embraced by the walls of the slots 15 and 16 so as to prevent torsion 60 of the ribs adjacent their point of engagement with the notch, it being understood that considerable strain is applied to the ribs at this point on axial movement of the canopy about the stick.

The runner 17 embodies the elements 18 and 19 which are similar in construction to the elements 3 and 4 of the hereinbefore described notch. The rib connecting stretchers 20 are provided with spherical lower 70 end portions or heads 21 which are fitted in the coöoperating cup portions 22 and 23 of the elements 18 and 19. Integral projecting portions 24 are formed on the heads 21 at an angle with respect to the rib and are adapted to be moved in the slots in the cup portions 22 and 23 on pivotal movement of the stretchers to their open or closed positions. These webs act in addition to the webs 14 hereinbefore described to prevent torsion on 80 the stretchers when the canopy is moved axially of the stick 1.

We claim:

1. In an umbrella structure, a stick, a runner movable thereon, a notch secured to 85 the stick and provided with a slotted cup portion, ribs having spherical heads mounted in the cups of the notches and having formed integral therewith projecting portions disposed at an angle with respect to the ribs 90 and movable in the slots of the said cup portions and adapted to limit the swing of the ribs, and stretchers connecting the ribs with the runner.

2. In an umbrella structure, a stick, a 95 notch secured thereon, ribs connected to the notches, a runner movable on the stick and provided with a slotted cup portion, stretchers connecting the ribs with the runner and provided with spherical heads fitted in the 100 cup of the runner, and integral projecting portions formed on the heads and at an an-

gle to the said stretchers and movable in the slots in the cup of the runner, on movement of the runner to an open and closed position.

5 3. In an umbrella, ribs having a vertical upper end, a projecting portion formed integral therewith and disposed at an angle to the ribs.

In testimony whereof we affix our signatures in presence of two witnesses.

JOSEPH KIRKLEY.
FRANK A. WHITE.
